UNITED STATES PATENT OFFICE.

EARL G. WATROUS, OF CHICAGO, ILLINOIS.

WATER-CLOSET.

1,106,122.

Specification of Letters Patent.

Patented Aug. 4, 1914.

Application filed August 3, 1908. Serial No. 446,503.

To all whom it may concern:

Be it known that I, EARL G. WATROUS, a citizen of the United States, residing at Chicago, in the State of Illinois, have invented 5 a certain new and useful Improvement in Water-Closets, of which the following is a description, reference being had to the accompanying drawings, forming part of this specification.

10 My invention relates to what are known as seat-actuated closed-tank closets, being closets in which the depression of the seat opens a valve which admits the water supply to a closed tank, which fills with water 15 while the seat is depressed, and then discharges into the closet when the pressure on the seat is removed.

It has for its principal object an improved construction, arrangement and operation of 20 the valves which control the admission of the water supply to the closed tank and its subsequent release and discharge therefrom.

In the accompanying drawings Figure 1 is a middle vertical section of the rear portion 25 of the closet and the valve casing and the valves supported thereon; Fig. 2 a top plan view of the parts shown in Fig. 1; Fig. 3 a cross sectional detail approximately on the line 3—3 of Fig. 1 with some of the interior parts left in elevation; and Fig. 4 a cross sectional detail on the line 4—4 of Fig. 1.

The same letters of reference are used to 30 indicate identical parts in the several views. As shown in Fig. 1, the closet bowl A is provided in its upper rear portion with a chamber B which communicates with the flushing rim C of the bowl by ports a, and directly with the bowl by ports b, and is 35 provided in its top with a central opening D, which in the present instance is approximately elliptical in shape. The top of the chamber B constitutes the seat-shelf of the closet bowl, and upon it rests a metal casing 40 E having an opening in its bottom coincident with the opening D in the top of the chamber B, and secured to the latter and the bowl of the closet by the bolts F shown in Fig. 3. A packing ring seated in a groove formed in 45 the bottom of the casing E around the opening therein secures a tight joint between the bottom of the casing and the top of the bowl. At its rear end the casing E is provided with a pipe connection G for the water supply 50 pipe, while the upper side of the casing is provided with a connection H for the lower

end of the pipe which leads upward to the closed tank (not shown) supported in the usual position above the closet.

A chamber J formed in the rear portion 60 of the casing E, in oper. communication with the connection H and pipe leading to the tank, communicates with the water supply through a central opening K in its rear wall, and with the interior of the main portion of 65 the casing E and the chamber D through a coincident but larger opening L in its front wall. The opening K in the rear wall of the chamber is controlled by a valve O, and that in the front wall by a valve P, 70 opening in opposite directions and both carried by the same valve stem Q. The front end of this valve stem has its support and bearing in a plug R screwed into an opening in the front wall of the casing E, while 75 its rear end is supported and guided by a disk or flange S snugly fitting within the pipe connection G. This disk or flange, which is provided with perforations or peripheral notches to permit the free passage 80 of the water, is in the present instance formed upon a short supplemental valve stem S' seated in a bore in the rear end of the main valve stem Q and having a conical front end whose point alone bears against 85 the end wall of the bore in the valve stem Q, for a purpose hereinafter described. The valve O is secured upon the stem S'. A coiled spring T bearing against the outer side of the flange S and confined within a 90 housing U coupled to the connection G by a nut U' serves to press all of the parts forward and yieldingly hold the valve O against its seat and the valve P away from its seat. When, however, the valve stem and valves 95 are forced rearward the valve P will be closed and the valve O opened, and water will be permitted to pass from the supply pipe through the chamber J and pipe connection H and pipe to the tank, filling the 100 latter to the limit permitted by the air in the tank. When the valve stem and valves are thereafter released the spring T will restore them to normal position, closing the valve O and cutting off the water supply, 105 and opening the valve P and permitting the tank to discharge its contents through the opening L into the chamber B, and thence to the closet bowl through the ports a and b, and through a suitable connection to the jet 110 of the closet, if the latter be of a character employing a jet.

The valve stem Q is operated, to open and close the valves O and P , in the manner and for the purpose described, by a connection with the closet seat V , the rearwardly and inwardly extended hinges W of which pass through stuffing boxes XX in the opposite sides of the casing E , Figs. 3 and 4, and their inner ends, projecting within said casing, are squared as shown in Fig. 1 and have secured upon them a hub Y provided with a pair of depending arms Z Z' embracing a sleeve or hub Q' secured upon the valve stem Q , as best shown in Fig. 3. The lower extremities of the arms Z Z' project in front of lateral studs or projections Z' Z' upon the sleeve or hub Q' , shown in Figs. 1 and 3.

In the normal position of the parts the seat V is slightly elevated, as in Fig. 1; and when it is depressed upon the closet bowl the lower ends of the arms Z Z' are swung rearward, carrying the valve stem and valves with them, and closing the valve P and opening the valve O . The tank is thereupon filled with water, and when the pressure upon the seat is relieved the spring T restores the parts to normal position, closing the valve O , and opening the valve P and discharging the contents of the tank into the closet.

For the purpose of permitting an adjustment of the parts which will cause the valve P to come to rest upon its seat at the instant the closet seat comes to rest upon the closet bowl, the flanged hub or sleeve Q' is adjustably mounted upon the valve stem Q by a threaded engagement therewith. Upon unscrewing and removing the plug R which supports the front end of the valve stem, a screw-driver may be inserted through the opening in the front wall of the casing E , from which such plug has been removed, and engaged with a nick in the front end of the valve stem, and the latter be turned to adjust the hub Q' forward or backward upon the stem, to bring about the proper relation between the movements of the valve P and closet seat. The provision of the supplemental valve stem S' for the valve O enables the latter to be readily removed, for inspection and repairs, without removing the valve stem Q and valve P ; while the pointed bearing of the front end of the stem S' against the end of the bore in the stem Q relieves the friction between the parts and enables the stem Q to be easily moved, in the manner and for the purpose above described, notwithstanding the strong pressure of the spring T .

The seat hinges W W terminate at their forward ends in horizontal plates W' W' secured to the top of the seat V by screws, and in vertical plates W^2 W^2 secured in like manner to the rear edge of the seat and having an overlapping joint X' as shown. This

construction provides a secure and rigid attachment of the hinges to the seat and strengthens and protects the latter.

Having thus fully described my invention, I claim:

1. In a water closet of the character described, the casing E having the pipe connections G and H and the chamber J having the valve openings K and L in its rear and front walls, the valve stem Q carrying the valve P coöperating with the opening L , the supplemental valve stem S' fitting in the rear end of the valve stem Q and carrying the valve O coöperating with the opening K , the spring T operating to press the valves and valve stems forward, and the seat V hinged to the casing E and operatively connected to the valve stem Q to force the same and the valves O and P rearward when the seat is depressed; substantially as described. 70 75 80 85

2. In a water closet of the character described, the casing E having the pipe connections G and H and the chamber J having the openings K and L in its opposite walls, the threaded valve stem Q having its front end supported and guided in the plug R in the front wall of the casing E , the hub Q' threaded upon the valve stem Q , the hinged seat V , an operative connection between said seat and the hub Q' upon the valve stem to cause the latter to be forced rearwardly when the seat is depressed, the coiled spring T pressing the valve stem forwardly, and the valves O and P carried by the valve stem and coöperating with the openings K and L , respectively; substantially as described. 90 95 100

3. In a water closet of the character described, the casing E having the pipe connections G and H and chamber J provided with the valve openings K and L in its opposite walls, the valve stem Q carrying the valves O and P coöperating with the openings K and L , respectively, and supported and guided at its front end in the screw plug R , the hub Q' threaded upon said valve stem, the seat V having its hinges W W journaled in the casing E , and the hub Y mounted on said hinges and provided with the depending arms Z coöperating with the hub Q' to force the latter and the valve stem rearward when the seat is depressed; substantially as described. 105 110 115

4. The combination of the casing E having the pipe connections G and H and the chamber J having the valve openings K and L , the valve stem Q carrying the valve P coöperating with the opening L and the supplemental valve stem S' seated in the rear end of the stem Q and carrying the valve O coöperating with the opening K , the spring T operating to press the valves and valve stem forward, and the seat hinges W W journaled in the casing E and operating 120 125 130

tively connected with the valve stem Q to force the latter and the valves rearward; substantially as described.

5. The combination of the casing E having the pipe connections G and H and the chamber J having the valve openings K and L in its opposite walls, the valve stem Q supported and guided at its front end in a support in the front wall of the casing E, 10 and carrying the valve P coöperating with the opening L, the supplemental valve stem S' fitting in the rear end of the valve stem Q and carrying the valve O and provided with the flange or disk S fitting the pipe 15 connection G, the housing U coupled to the pipe connection G, the spring T confined in the housing U and operating to press the valve stem and valves forward, and the seat hinges W W journaled in the casing E and 20 operatively connected with the valve stem Q to force the latter and the valves rearward; substantially as described.

6. The combination of the casing E having pipe connections G and H and chamber 25 J provided with the valve openings K and L in its opposite walls, the valve stem Q supported and guided at its front end in the screw plug R and carrying the valves O and P coöperating with the openings K and L, the hub Q' threaded upon the stem Q, 30 and the seat hinges W W journaled in the casing E and operatively connected with the hub Q' to force the latter and the valve

stem and valves rearwardly; substantially as described.

7. The combination of the casing E having the pipe connections G and H and the chamber J having the valve openings K and L in its opposite walls, the valve stem Q supported and guided at its front end in the screw plug R and carrying the valves O and P coöperating with the openings K and L, respectively, the hub Q' threaded upon the stem Q, the seat hinges W W journaled in the casing E, and the hub Y mounted upon 40 said hinges and having the depending arm Z engaging the hub Q'; substantially as described.

8. A casing adapted to be applied to a closet containing a water passage, comprising an inlet connection D and inclosing a chamber J having opposite walls provided with inlet and outlet ports K and L, in line with each other and within inlet connection, an opening in the exterior wall of the casing 50 in line with said ports a plug R normally closing said opening, a valve stem Q carrying a valve P for port L and guided at one end within the plug, a second valve stem S' carrying valve O for port K and slidably 55 fitting a bore of the stem Q and means for reciprocating the stem Q.

EARL G. WATROUS.
